UNITED STATES PATENT OFFICE.

ANDREW HINES, OF ARLINGTON, KENTUCKY.

HAY-RACK.

SPECIFICATION forming part of Letters Patent No. 620,587, dated March 7, 1899.

Application filed February 8, 1898. Serial No. 669,585. (No model.)

To all whom it may concern:

Be it known that I, ANDREW HINES, a citizen of the United States, residing at Arlington, in the county of Carlisle and State of Kentucky, have invented a new and useful Hay-Rack, of which the following is a specification.

The invention relates to improvements in hay-racks.

The object of the present invention is to improve the construction of hay-racks and to provide a simple and comparatively inexpensive one adapted to be readily applied to any ordinary wagon body or bed and capable of being mounted thereon and removed therefrom in sections, so that one person can readily handle it.

The invention consists in the construction and novel combination and arrangement of parts, as hereinafter fully described, illustrated in the accompanying drawings, and pointed out in the claims hereto appended.

In the drawings, Figure 1 is a perspective view of a hay-rack constructed in accordance with this invention and shown applied to a wagon-body. Fig. 2 is a longitudinal sectional view. Fig. 3 is a transverse sectional view. Fig. 4 is a detail view of one of the cross-bars of one of the lower sections of the sides of the rack. Fig. 5 is a detail view of one of the detachable braces.

Like numerals of reference designate corresponding parts in all the figures of the drawings.

1 and 2 designate sides and ends of a hay-rack which is mounted upon a wagon body or box 3 of the ordinary construction. The sides 1, which are detachably mounted upon the sides of the wagon body or bed, are composed of upper and lower sections 4 and 5, hinged together at their adjacent portions, and the upper one is adapted to fold downward on the lower one. The lower section 5 is composed of horizontal bars or slats and transverse connecting-bars 6, suitably secured to the horizontal slats or bars. The upper section 4, which is constructed similar to the lower section, is provided at the lower ends of its transverse bars 7 with eyes 8, which are detachably engaged by hooks 9 of the bars 6 of the lower section. The hooks and eyes form a hinge-joint and also permit the sections to be disconnected when desired.

The lower ends of the bars 6 are cut at an angle and fit against the outer faces of the sides of the wagon-body, and they are provided with eyes 10, which are engaged by hooks 11 of anchoring-bars 12. The anchoring bars or rods 12, which are arranged on the inner faces of the sides of the wagon-body, have their lower portions extended through the bottom thereof and threaded to receive nuts 13, which detachably secure the anchoring-bars in position on the wagon-body. The upper ends of the anchoring-rods are angularly bent to form hook-shaped portions 14, and the terminals of the latter are extended upward to form arms 15, which are provided with the said hooks 11. The inner ends of the bars 6 are recessed at their upper faces to receive the outer sides of the hook-shaped portions of the anchoring-rods, which serve to secure the lower sections of the sides of the hay-rack to the wagon-body and at the same time prevent the bars 6 from moving laterally thereon.

The lower threaded ends of the anchoring-rods extend through transverse cleats 16, which project beyond the sides of the wagon-body, and the projecting ends of the cleats 16 are provided with perforations receiving and forming sockets for detachable pins 17 of braces 18. The braces 18, which are detachably stepped in the openings or sockets of the cleats by means of the said pins 17, have their upper ends bifurcated at 19 to receive the bars 6 and are detachably pivoted to the same by means of bolts 20. The braces 18, which have their lower ends beveled to fit the cleats, extend outward from the sides of the wagon-body at an inclination and form firm supports for the sides of the hay-rack.

The sides and the ends of the hay-rack taper in length, as clearly illustrated in the drawings, to close the spaces at the corners of the rack, and the ends 2 are constructed exactly the same as the sides, being composed of upper and lower sections detachably hinged together by hooks and eyes. The lower sections of the ends are supported by inclined braces 18 and are detachably secured to the wagon-body by anchoring bars or rods.

The top bars of the sides and ends of the rack are connected by suitable fastening devices, such as hooks 21 and eyes 22 or any

other suitable fastening devices, to prevent the upper sections of the sides and ends from folding accidentally.

5 The hay-rack may be readily removed from the wagon-body by withdrawing the pivot-bolts of the braces and removing the nuts of the anchoring-rods, and the outer or upper sections of the sides and ends may be folded on the lower sections.

10 The invention has the following advantages: The hay-rack is simple and comparatively inexpensive in construction and is adapted to be readily applied to any ordinary wagon-body without injuring or necessitating 15 any alteration in the construction of the same. The sections of the hay-rack are adapted to fold on each other and are detachably connected, and the parts may be assembled one at a time, so that one person may place the 20 hay-rack on and remove it from a wagon-body.

Changes in the form, proportion, and minor details of construction may be resorted to without departing from the spirit or sacrificing any of the advantages of this invention.

25 What I claim is—

1. In a device of the class described, the combination with a wagon-body, of an anchoring bar or rod arranged at the inside of the body, a hook projecting from the upper end of the 30 anchoring-bar and engaging the upper edge of the wagon-body, an arm extending from the outer portion of the hook and projecting from the wagon-body, and a hay-rack section detachably engaging the arm and secured by the latter to the wagon-body, substantially as described.

2. In a device of the class described, the combination with a wagon-body, of an anchoring-rod arranged inside of the body, a hook arranged at the upper end of the anchoring-rod 40 and engaging the upper edge of the body, an arm extending outward from the hook, the hook 11 located at the outer end of the arm, and a hay-rack section fitting against the 45 wagon-body and provided with an eye engaging the hook 11, substantially as described.

3. In a device of the class described, the com-

bination of a wagon-body, anchoring-rods engaging the upper edge of the wagon-body, arms extending from the anchoring-rods, a 50 hay-rack section detachably engaging the arms, and inclined braces hinged at their upper extremities to the hay-rack section and having their lower ends detachably stepped on the wagon-body, substantially as described. 55

4. In a device of the class described, the combination with a wagon-body, of anchoring-rods arranged inside the body and provided with hook-shaped upper portions engaging the upper edges of the body, said anchoring-rods having arms extending upward from the outer sides of the hook-shaped portions and terminating in hooks, a hay-rack section provided with eyes to engage the hooks and having transverse bars recessed to receive the 60 outer sides of the hook-shaped portions, and inclined braces provided at their lower ends with pins and detachably stepped on the wagon-body, the upper ends of the braces being bifurcated and detachably secured to the 65 transverse bars, substantially as described.

5. In a device of the class described, the combination of a wagon-body, hooks arranged at the upper edges of the wagon-body, sides composed of sections detachably hinged together 75 and provided with eyes to engage the hooks at the sides of the wagon-body, ends composed of sections hinged together detachably and provided with eyes to engage the hooks at the ends of the wagon-body, inclined braces 80 detachably stepped on the wagon-body and secured at their upper ends to the inner sections of the sides and ends of the hay-rack, and fastening devices detachably connecting the ends of the upper sections of the sides 85 and ends of the hay-rack, substantially as described.

In testimony that I claim the foregoing as my own I have hereto affixed my signature in the presence of two witnesses.

ANDREW HINES.

Witnesses:
